United States Patent Office

Des. 233,369
Patented Oct. 22, 1974

233,369

MICROFILM XEROGRAPHIC MACHINE

Leonard Schachner, Pittsford, N.Y., assignor to
Xerox Corporation, Stamford, Conn.

Filed Nov. 13, 1972, Ser. No. 306,239

Term of patent 14 years

Int. Cl. D16—03

U.S. Cl. D61—1 Q

FIG. 1

FIG. 2

F/G. 3

F/G. 4

FIG. 1 is a top plan view of a microfilm xerographic machine showing my new design;

FIG. 2 is an elevational front view thereof;

FIG. 3 is an elevational right side view thereof;

FIG. 4 is an elevational left side view thereof; and

FIG. 5 is an elevational rear view thereof.

I claim:

The ornamental design for a microfilm xerographic machine, as shown.
